UNITED STATES PATENT OFFICE

2,687,622

DISPLAY STAND FOR FROZEN FOOD
AND THE LIKE

Ralph Robbins, Jamaica, N. Y.

Application March 15, 1952, Serial No. 276,773

1 Claim. (Cl. 62—91.5)

1

The present invention relates to new and useful improvements in display and advertising devices, being specifically designed for displaying frozen foods, beverages, and the like in stores, in self-service sections of super-markets, and in other places frequented by prospective purchasers.

One object of the present invention is the provision of a device of the character described which will provide a continuous cooling of the displayed articles independently of electrically or mechanically operated stationary cooling installations and fixtures, so that this device can be placed temporarily or permanently into any section of a store or the like.

Another object of the present invention is the provision of a device of the character described which has its cooling medium normally hidden by the merchandise contained in the device, so that the merchandise appears as being displayed in an ordinary container or basket, free from any cooling machinery, and which consequently will cause an element of surprise and produce a pleasing impression of freshness when being touched or more closely scrutinized by prospective purchasers, thus tending to stimulate a desire to partake of the articles so displayed.

A further object of the present invention is the provision of a device of the character described which is light in weight and collapsible, so that it can be easily stored when not in use or transported from place to place, which is of a pleasing outer appearance, and which is simple in construction, so that it can be manufactured and sold at a very reasonable price, but which is also sturdy, durable and well adapted to withstand the rough usage to which devices of this type frequently are subjected.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

In the accompanying drawing a preferred form of the invention has been shown.

In said drawing:

Figure 1 is a top plan view of a preferred embodiment of my invention;

Fig. 2 is a side elevation; and

Fig. 3 is a cross-sectional view on the line 3—3 of Fig. 1.

2

Similar reference characters refer to similar parts throughout the several views.

In the drawing the numerals 2 and 4 denote a pair of inverted U-shaped members each of which has a longitudinal web portion 3 and a pair of downwardly extending flange portions 5 which intermediate their ends 7 are pivotally connected to the flange portions of the other U-shaped member so that said U-shaped members constitute a collapsible scissors stand. Longitudinal hook members 6 engage with their upper portions the web portions of the members 2 and 4, and are attached to the inner sides of opposite side portions of an open wire basket 8, to which the lower ends 10 of the hook members 6 are pivoted or otherwise secured. A primarily flat bag or envelope member 12, having double bottom and side wall portions encompassing the outer sides of the bottom and side wall portions of the basket 8, has its edge sections 14 extended over the upper edges of the basket 8 and into the same, as may be seen in Figs. 1 and 3. Portions of the hook members 6 which extend into the basket 8 overlay the edge sections 14 of the envelope member 12 without piercing the same. Any suitable heat and cold insulation, such as fibre glass or the like is placed between the double walls of the envelop 12. A pair of casings 16, which has perforated side walls and which are provided with removable covers 18, are placed into the basket 8 and are preferably in spaced relation to each other as well as the two opposite side wall portions of the basket 8.

While the top of the device can be left open, or can be closed with any suitable, preferably transparent lid, I prefer to provide the open top of the basket 8 with a transparent inwardly and upwardly inclined frame or lid member consisting of trapezoid-shaped transparent plates 20 of plastic material, such as "Lucite" or the like, whose ends are joined to each other by means of angle bars 22 or the like. This arrangement will prevent the merchandise (not shown) piled up in the basket 8 and covering the casings 16, from falling out of the device, and it also will tend to prevent to a certain extent a radiation of the coolness emanating from Dry Ice 26 or from any other suitable cooling media placed into the casings 16 and separated by the latter from said merchandise.

The flange portions of the member 2 are pivoted at 24 to the flange portions of the member 4, so that the framework can be collapsed after the removal of the basket 8 therefrom.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having thus fully described my said invention, what I claim as new and desire to secure by Letters Patent is:

A display stand for frozen food and the like comprising a pair of inverted U-shaped members each of which has a longitudinal web portion and a pair of downwardly extending flange portions which intermediate their ends are pivotally connected to the flange portions of the other U-shaped member so that said U-shaped members constitute a collapsible scissors stand, a wire basket interposed between the web portions of said U-shaped members having bottom and side wall portions and being open at its top, an envelope member having double bottom and side wall portions encompassing the outer sides of the

bottom and side wall portions of said basket and extending over the upper edges of said basket into the interior thereof, hooks engaging the web portions of said U-shaped members being secured to the inner sides of opposite side wall portions of said basket and extending outwardly over the upper portions thereof, heat and cold insulating material being interposed between the double bottom and side wall portions of said envelope member, a pair of longitudinal casings each having a bottom and perforated side walls being provided in said basket and in spaced relation to each other as well as to opposite side wall portions of the basket and being adapted for containing a refrigerating substance and for separating the same from articles placed into said basket, and a transparent inwardly and upwardly inclined frame attached to the open top portions of said basket being removably placed upon the same.
